S. KISLEVITZ.
MACHINE FOR INSPECTING AND CUTTING FABRICS.
APPLICATION FILED APR. 28, 1920.

1,414,818.

Patented May 2, 1922.

UNITED STATES PATENT OFFICE.

SAMUEL KISLEVITZ, OF NEW YORK, N. Y., ASSIGNOR TO KAUMAGRAPH COMPANY, OF NEW YORK, N. Y., A CORPORATION OF NEW YORK.

MACHINE FOR INSPECTING AND CUTTING FABRICS.

1,414,818.

Specification of Letters Patent.

Patented May 2, 1922.

Application filed April 28, 1920. Serial No. 377,293.

To all whom it may concern:

Be it known that I, SAMUEL KISLEVITZ, a citizen of the United States, and resident of New York city, in the county and State of New York, have invented certain new and useful Improvements in Machines for Inspecting and Cutting Fabrics, of which the following is a specification.

This invention is intended to provide a simple and effective machine for the inspection and cutting up of fabrics into short lengths and is particularly advantageous in connection with the inspection of long strips of paper upon which are placed the figures or legends forming decalcomania or transfer stamps for the marking of fabrics in a well known manner.

To this end the invention consists broadly speaking in a rotary drum made in relatively adjustable sections provided with parallel adjustable guide bars arranged on the periphery of the drum to form guides for the cutting knife, the same being rotatably controlled as will be explained. This and other features characterizing the invention will be particularly described in this specification and will be defined in the claims here-to annexed.

In the accompanying drawings I have illustrated a simple form and arrangement of mechanism embodying the principles of this invention, in which—

Figure 1 is a plan view of the assembled machine.

Figure 2 is a side elevation thereof.

Figure 3 is a detail in plan view, of the setting scale.

Figure 4 is a detail in cross section showing the drum head, taken in line 4—4 of Figure 2.

Figure 5 is a detail in section on plane 5—5 of Figure 2.

Figure 6 is a front elevation showing the detail of the strip anchoring plate.

The machine shown in the drawings is particularly intended for use in connection with the inspection of cutting up of decalcomania or transfer stamps in which the individual stamps or figures are imprinted on long strips of thin paper, a short interval or blank space being left between each successive group of the stamped figures to enable the strips to be cut into short lengths for use.

In the practice of this invention according

to the form illustrated in the drawings I provide a suitable frame work 1 having at one end notched uprights 2 to receive the journals of the roll 30 which carry the long roll or strip of paper bearing the transfer designs or stamps. The frame is provided with suitable horizontal journals 3 for rotatably supporting the drum shaft 4 which is provided with suitable hubs 5 near either end to which are attached the arms 6 forming the fixed spider or drum support by which the drum sections are adjustably supported.

The drum itself comprises the opposite head sections 8 each of which is provided with parallel cleats 9 separated by a space 70 corresponding to the width of the arms 5 of the spider so that each section or half of the drum is slidable upon the spider arm 5 toward and away from the other in order to diminish or increase the circumferential distance around the drum which adjustment is intended for the purpose of bringing the blank or unprinted portions of the strip in registry one above the other as the strip is wound around the circumference of the revolving drum. Each of the spider arms 5 is provided with a longitudinal slot through which is passed a headed bolt 10 passing through an aperture in the head of the drum aligned with said slot having at its outer 85 end a winged clamping nut 11 so that the drum head 8 will be clamped firmly to the spider arms 5 in their various positions of adjustment.

To facilitate proper and accurate adjustment of the drum for differently spaced strips a graduated scale 7 is placed on the spider arm 5 adjacent to the inside edges of the head 8 so as to indicate the exact separation of said heads from which the proper adjustment may be determined according to the lengths of the printed portions of the paper strip.

The periphery of the drum consists of a circumferential series of parallel slats or bars 18. At intervals around the drum a number of these bars are made adjustable in a circumferential direction so that two adjacent bars may be properly set to form a guide for the cutting knife which is passed between them lengthwise of the drum to sever simultaneously the numerous layers of paper that have been wound upon the drum.

This circumferential adjustment of the bars 18 may be effected in any suitable manner. I have shown rings 15 provided at suitable intervals with longitudinal slots 16 5 the rings being secured to the outer faces of the drum heads 8 adjacent to the peripheral edge of the drum sections. The rings 15, of course, are made in as many sections as are the drum heads so as to move therewith. 10 The peripheral bars or slats 18 overhang the slotted rings 15 and are provided with perforations for admitting clamping bolts 17 which pass through the fastening slots 16 and the fastening rings 15. With this arrangement those peripheral bars which are 15 located at points where the unprinted portions of the stamp strip are located in the winding operation, may be adjusted to provide the right width of slot for receiving the 20 blade of the cutting knife which is drawn through the slot between two adjacent bars to sever the strip into the short lengths.

In order to hold the free ends of the severed pieces until the operator is ready to remove them I provide clamping members 31 which consist of spring fingers secured by set screws to the outer faces of the appropriate slats or bars 18 to overlap the wrapped long strip of paper on either side of the severing 30 line.

The drum is rotated by suitable belt connections running from the driving pulleys 23 on the shaft 4 to and around pulley 22 which is driven directly from a variable 35 speed electric motor 19 whose speed is controlled by the rheostat 20 whose movable arm is connected with a foot treadle 21. This variable speed enables the operator to inspect the strip as it is being wound on the 40 drum with more or less care as may be needed and permits the machine to be entirely stopped at will.

The drum may be made in any convenient number of sections although in this case I 45 have shown but two sections each of whose heads are substantially semi-circular and which are united by cross bars 12.

To fasten the first end of the stamp bearing strip a suitable clamping or holding device 50 should be provided. In this case I have shown a clamping plate 13 extending along the inside face of one of the cross bars 12 and provided with notches to receive clamping screws 14 so that the first end of the paper 55 may be inserted between the cross bar 12 and the clamping plate 13 which latter is pressed against the cross bar to pinch and hold the end of the strip.

The width of the space separating the 60 printed portions of the strip is sufficient to compensate for the slight offset due to the slightly increasing diameter of the successive layers of paper wound on the drum. In fact, twenty-five or thirty layers of this transfer 65 stamp strip may be wound on the drum and

will be registered with sufficient accuracy to permit simultaneous cutting of all the layers with the aid of the adjustable bars forming the cutting guides for the cutting knife.

What I claim is:

1. In a machine for inspecting and cutting fabric, the combination of a rotary drum comprising a plurality of sections adjustable toward and away from each other to vary the circumferential measurement of the 75 drum, knife guiding bars adjustable about the periphery of the drum arranged to form guides for a cutting knife, and an indicating scale extending in the direction of the movement of the drum sections toward and 80 away from each other to indicate the proper adjustments of the sections for use, substantially as described.

2. In a machine for inspection and cutting fabric, the combination of a rotary drum, 85 transverse slats arranged in parallelism around the periphery of said drum and being adjustable circumferentially of the drum in order to form adjustable guides for cutting the fabric, said drum being divided 90 into sections adjustable toward and away from the center, and means for rotating said drum at different speeds, substantially as described.

3. In a machine for inspecting and cutting fabrics, the combination of an expandable winding drum, a peripheral series of adjustable bars mounted on said drum some of said bars being made circumferentially adjustable thereon, means for gripping one 100 end of the fabric, means for temporarily holding the layers of fabric in position for the cutting operation, and driving mechanism for rotating the drum at different speeds, substantially as described.

4. In a machine for inspecting and cutting fabrics, the combination of a rotary spider having longitudinally slotted radial arms, a sectional winding drum whose sections comprise parallel end heads and peripheral slots, the end heads being provided with guide cleats engaging the arms of said spider so as to have adjustable sliding support thereon, clamping means passing through said slots and the heads of the 115 drum sections for adjustably clamping the cylinder sections in proper relationship, knife guiding members comprising transverse peripheral slats adjustable circumferentially of the drum in order to position 120 them for guiding the cutting knife, substantially as described.

5. In a machine of the class described the combination of a rotary spider, a cylindrical drum formed of a plurality of sections adjustable toward and away from each other on said spider, means for clamping said drum sections in proper position of adjustment, peripheral guide bars mounted on each section and clamping fingers re- 130

movably supported on the guide bars for holding the wound on layers of fabric against the periphery of the drum after the fabric has been severed, substantially as described.

6. In a machine of the class described, the combination of a rotary spider, a sectional winding cylinder whose sections are adjustably secured to said spider so as to 10 permit variations in the circumference of the cylinder, a clamping plate for gripping the free end of the fabric to be cut, adjustable guide bars arranged on the periphery of said cylinder to form guides for the cutting knife, and clamping fingers arranged 15 to hold that portion of the fabric next to the

line of cutting in position against the cylinder, substantially as described.

7. In a machine of the class described, the combination of a winding cylinder comprising a plurality of sections adjustable toward and away from each other each section comprising end heads and peripheral bars and having a circumferentially slotted member, fastening means passing through said 25 slots and having engagement with peripheral bars to hold them in proper position of circumferential adjustment to form guides for a cutting knife, substantially as described.

In witness whereof, I have subscribed the 30 above specification.

SAMUEL KISLEVITZ.
